US00D334549S

United States Patent [19]
Esquibel

[11] **Patent Number:** **Des. 334,549**
[45] **Date of Patent:** **** Apr. 6, 1993**

[54] **WINDSHIELD WIPER BLADE
ATTACHMENT IN BREAKING ICE FORMED
BETWEEN THE BLADE AND WINDSHIELD**

4,670,933 6/1987 Toplenszky 15/250.07
4,700,424 10/1987 Hagen 15/250.07

[76] **Inventor:** **George R. Esquibel, P.O. Box 575,
Pensaco, N. Mex. 87553**

Primary Examiner—James M. Gandy
Attorney, Agent, or Firm—Terry M. Gernstein

[**] **Term:** **14 Years**

[57] **CLAIM**

[21] **Appl. No.:** **775,375**

The ornamental design for a windshield wiper blade attachment for breaking ice formed between the blade and windshield, as shown and described.

[22] **Filed:** **Oct. 15, 1991**

DESCRIPTION

[52] **U.S. Cl.** **D12/155**

FIG. 1 is a perspective view of the windshield wiper blade attachment for breaking ice formed between the blade and windshield embodying the design of the present invention;

[58] **Field of Search** **D12/155; 15/250.03,
15/250.05, 250.06, 250.19, 250.07; D13/112**

FIG. 2 is a front elevational view thereof;
